CLAIM

The ornamental design for a casing bead with a ribbed and perforated flange, as shown and described.

DESCRIPTION

FIG. 1 is a top perspective view of a casing bead with a ribbed and perforated flange, showing our new design;

FIG. 2 is a bottom perspective view of the casing bead with a ribbed and perforated flange of FIG. 1

FIG. 3 is a rear elevational view of the casing bead with a ribbed and perforated flange of FIG. 1;

FIG. 4 is a front elevational view of the casing bead with a ribbed and perforated flange of FIG. 1;

FIG. 5 is a right elevational view of the casing bead with a ribbed and perforated flange of FIG. 1;

FIG. 6 is a left elevational view of the casing bead with a ribbed and perforated flange of FIG. 1;

FIG. 7 is a top plan view of the casing bead with a ribbed and perforated flange of FIG. 1; and,

FIG. 8 is a bottom plan view of the casing bead with a ribbed and perforated flange of FIG. 1.

The broken lines in FIGS. 1-5 and 7-8 are included for purposes of illustrating portions of the casing bead with a ribbed and perforated flange that form no part of the claimed design. The casing bead with a ribbed and perforated flange is shown with a symbolic break in its length. The symbolic break is depicted using dash-dot lines and brackets. The appearance of any portion of the casing bead with a ribbed and perforated flange between and including the break lines forms no part of the claimed design.
